CLAIM

The ornamental design for a base for medical accessory, as shown and described.

DESCRIPTION

FIG. 1 is a top perspective view of a base for a medical accessory;

FIG. 2 is a bottom perspective view thereof; ps FIG. 3 is a front-side view thereof;

FIG. 4 is a back-side view thereof;

FIG. 5 is a right-side view thereof;

FIG. 6 is a left-side view thereof;

FIG. 7 is a top-side view thereof;

FIG. 8 is a bottom-side view thereof;

FIG. 9 is a top perspective view of a base for a medical accessory;

FIG. 10 is a bottom perspective view thereof;

FIG. 11 is a front-side view thereof;

FIG. 12 is a back-side view thereof;

FIG. 13 is a right-side view thereof;

FIG. 14 is a left-side view thereof;

FIG. 15 is a top-side view thereof; and,

FIG. 16 is a bottom-side view thereof.

The broken lines represent portions of the base for a medical accessory and environmental subject matter and form no part of the claimed design.

1 Claim, 12 Drawing Sheets
